The ornamental design for a toy car, as shown and described.

DESCRIPTION

FIG. 1 is a front, right and top perspective view of a toy car, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 1; and,

FIG. 12 is an enlarged view of portion 12 shown in FIG. 2. The evenly spaced broken lines shown in the drawings illustrate portions of the toy car that form no part of the claimed design. The dot-dash-dot broken lines in FIGS. 1, 2, 9, 10, 11, and 12 depict boundaries of the detailed enlargement that form no part of the claimed design.
